UNITED STATES PATENT OFFICE

113,121

DESIGN FOR BAR MATERIAL FOR OPHTHALMIC MOUNTINGS

Edward M. Splaine, Southbridge, Mass., assignor
to American Optical Company, Southbridge,
Mass., a voluntary association of Massachusetts

Application June 29, 1938, Serial No. 78,152

Term of patent 14 years

To all whom it may concern:

Be it known that I, Edward M. Splaine, a citizen of the United States of America, residing at Southbridge, in the county of Worcester and State of Massachusetts, have invented a new, original, and ornamental Design for Bar Material for Ophthalmic Mountings, of which the following is a specification, reference being made to the accompanying drawing, forming a part thereof.

The figure in the drawing is a greatly enlarged perspective view of a piece of bar material for use in forming parts of an ophthalmic mounting and embodying my new design.

The characteristic features of the design reside in the provision of a bar having a relatively narrow, continuous, smooth, central, longitudinal surface, having opposed longitudinal, corrugated

side surfaces and having bead-like longitudinal edges on the opposed sides of said corrugated surfaces. The relatively central, longitudinal surface gives forth the appearance of a continuous, brilliant ribbon when light impinges thereon and the opposed, corrugated surfaces produce a dull satin-like appearance as compared with said central ribbon-like reflective surface when viewed at a slight distance therefrom.

The essential features of the design reside in the portions of the bar which are shown in full lines in the drawing.

I claim:

The ornamental design for bar material for ophthalmic mountings, substantially as shown and described.

EDWARD M. SPLAINE.
